UNITED STATES PATENT OFFICE.

JOHN O. SMITH, OF CLEVELAND, OHIO.

UNDER-WATER EXHAUST AND MUFFLER.

977,976.

Specification of Letters Patent.

Patented Dec. 6, 1910.

Application filed August 12, 1910. Serial No. 576,930.

To all whom it may concern:

Be it known that I, JOHN O. SMITH, a citizen of the United States, residing at Cleveland, in the county of Cuyahoga and State of Ohio, have invented certain new and useful Improvements in Under-Water Exhausts and Mufflers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an underwater exhaust fitting or attachment for motor boats and the like, and it has for its object to eliminate the noise from the exhaust of an internal combustion engine without back pressure on the engine.

The exhaust from explosive engines have for some time been piped below the water line in yachts and launches and various attachments or fittings have been applied to the skin of hull at a point where the exhaust pipe passes through the planking, but in every instance the employment of such devices cause more or less back pressure on the engine, and some to such an extent that the power of the engine is materially reduced and therefore wasted.

It is the object of this invention to not only remove the back pressure from the engine but to actually assist in drawing the exhaust therefrom by providing a rarefied chamber to receive the exhaust in such manner that the exhaust leaves the exhaust pipe at less than atmospheric pressure.

With these objects in view the invention consists in the novel construction of the underwater exhaust fitting and particularly in the location and arrangement of the baffle plates therein and in the position of the ports or openings which in conjunction with the said baffle plates produces an aspirating action when the boat or vessel to which the fitting is applied is moving forward in water.

Referring to the accompanying drawings: Figure 1 is a bottom plan view of the under water exhaust fitting. Fig. 2 is a rear elevation of the same. Fig. 3 is a longitudinal sectional view through the fitting and boat planking. Fig. 4 is a side elevation, the boat planking being shown in section and Fig. 5 is a plan showing interior of fitting.

Like numerals of reference indicate the same parts throughout the several figures in which:

1 indicates the under water exhaust fitting and 2 the boat planking to the outer skin of which the fitting 1 is removably secured by through bolts 3, the fitting 1 being provided with a plurality of lugs 4 to receive the fastening bolts 3.

As will appear from the drawings, the fitting 1 is long and narrow, having its greatest depth at its forward end and gradually decreasing in depth as it progresses rearwardly. The bottom 5 is substantially flat and curves up to meet the sides 6, the forward end 7 being well rounded as shown. The upper edge of each side 6 is provided with a series of tapering ports or openings 8 having their greatest depth at their rear ends, each port or opening terminating at a baffle plate 9, which as shown in Fig. 5 are obliquely disposed within the long tapering chamber 10 formed by the exhaust fitting 1, in such manner that a gradually decreasing passage 12 is provided between each series of baffle plates, the said baffle plates increasing in length in their rearward progression as clearly shown in Fig. 5. A plurality of ports or openings 13 are provided one after the other in the bottom 5, the combined areas of the ports or openings 13 and the ports or openings 8 in the sides of the fitting being greatly in excess of the area of the engine exhaust pipe 14, it being of course understood that the size and capacity of the fitting should be varied to properly accommodate and handle the exhaust from engines of different horse powers.

Having thus described the construction of the under water exhaust fitting, its operation is as follows: The fitting being conveniently applied to the skin of the boat at a point below the water line thereof, and in such manner that the exhaust pipe 14 passes through the planking at the forward end of the fitting as shown in Fig. 3, the exhaust from the engine enters the chamber 10 at the forward and deepest part thereof. As the boat is moving forward, the water passing by the sides and bottom of the fitting produces an aspirating action at each of the ports or openings 8 and 13, the oblique position of the baffle plates 9 prevent the water from entering the chamber 10, while at the same time this construction deflects the exhaust into the side ports or openings 8. In

order to insure a proper distribution of the exhaust through all of the side ports or openings 8 the chamber 10 decreases in depth as it progresses rearwardly, while 5 the baffle plates 9 increase in length in their rearward progression which gradually decreases the width of the passage 12 toward the rear of the fitting, this gradual reduction in area of the chamber 10 insures a 10 uniform disposition of the exhaust through all of the ports or openings in the fitting and as the combined area of said ports are as before stated largely in excess of the areas of the exhaust pipe 14, back pressure on the 15 engine is eliminated while the particular form and arrangement of the ports and baffle plates creates an aspirating action which maintains the pressure within the chamber 10 less than atmospheric thus 20 relieving the exhaust from the back pressure to which it would be subjected if open to the atmosphere.

Having thus fully described the invention what is claimed as new and what is desired 25 to secure by Letters Patent of the United States is—

1. An underwater exhaust fitting comprising a bottom and sides forming a chamber, the said chamber decreasing in depth as it 30 progresses to the rear of the fitting, the upper edge of each side of the fitting being provided with a plurality of ports or openings tapered in such manner that the greatest depth of said ports or openings is 35 at the rear ends thereof, a plurality of baffle plates obliquely disposed within the said chamber and arranged to deflect the exhaust

through the said ports or openings, the said baffle plates increasing in length in their rearward progression in such manner as to 40 form a tapering passage in the fitting and a plurality of ports or openings arranged one after the other in the bottom of the fitting.

2. An underwater exhaust fitting comprising 45 a chamber to receive the exhaust, said chamber decreasing in depth as it progresses toward the rear of the fitting, a plurality of tapered ports or openings along the top of the chamber at each side thereof, a plurality of baffle plates within the chamber and associated with said ports or openings to deflect the exhaust therethrough, and a port or opening in the bottom of the chamber. 50

3. An underwater exhaust fitting comprising 55 a chamber, a plurality of ports or openings in each side of said chamber, a port or opening in the bottom of the chamber and a plurality of baffle plates within the chamber and associated with the ports or openings in the sides thereof to deflect the exhaust 60 from the chamber through said ports or openings.

4. An underwater exhaust comprising a 65 chamber provided with a plurality of ports or openings in each side thereof, and a plurality of baffle plates associated with said ports or openings to deflect the exhaust through said ports or openings.

In testimony whereof, I affix my signature, in presence of two witnesses.

JOHN O. SMITH.
